UNITED STATES PATENT OFFICE

165,514

HAIRBRUSH

Eric Leopold Hugo Cosby, London, England, assignor to G. B. Kent & Sons Limited, London, England, a corporation of England

Application March 27, 1951, Serial No. 14,645
In Great Britain October 5, 1950

Term of patent 14 years

(Cl. D36—10)

To all whom it may concern:

Be it known that I, Eric Leopold Hugo Cosby, a subject of the King of Great Britain, Northern Ireland, and the Isle of Man, residing at 24 Old Bond Street, London, England, have invented a new, original, and ornamental Design for a Hairbrush, of which the following is a specification, reference being had to the accompanying drawing, forming part thereof.

Fig. 1 is a perspective view of a hairbrush, showing my new design.

Fig. 2 is a side elevation.

Fig. 3 is a plan.

Fig. 4 is a section on line a—a.

Fig. 5 is a section on line b—b.

I claim:

The ornamental design for a hairbrush, as shown.

ERIC LEOPOLD HUGO COSBY.
